DEVICE FOR RIPPING OPEN PAPER ENVELOPES

Anna Dora Thieme, Hanover, Germany, assignor
to the firm H. Bahlsen's Keksfabrik A. G.,
Hanover, Germany

Application November 28, 1934, Serial No. 755,172
In Germany November 29, 1933

1 Claim. (Cl. 229—51)

The known devices for ripping open the paper wrapping of cartons in the form of prisms, for example four-sided prisms, operate in such a manner that, on the lid part or a stiff insertion between the lid part and the wrapping being raised, the portion of the wrapping, which is above the lid part, can be ripped open, or that this portion of the wrapping, which is above the lid part, is adapted to be ripped open by means incorporated in the wrapping. In ripping devices of the latter kind threads sewn into the wrapping, known as rip threads, were formerly in general use. As a substitute for the rip threads it has been proposed to fold together the two 10 transversely placed marginal parts of the wrapping paper, which come together when the package is being wrapped, at the front edge of the carton lid, to lay them over the top edge of the front wall of the carton and thereupon to cover 15 and fix the projecting ends of the fold, when folding in the side parts of the wrapping, the exposed middle part of the fold serving as the place to be taken hold of for ripping the wrapping. This part need not necessarily be laid 20 over the top edge of the front wall of the carton, but may be disposed at any other place of the carton wrapping.

The provision of such a ripping fold composed 25 of strip-like parts of the wrapping paper forms the subject matter of the present invention. But, whilst in the known arrangement of this kind the marginal parts of the wrapping paper were folded together, according to the present invention the ripping tab is formed from a transverse fold which is picked up from the surface of 30 the wrapping paper and is ripped. In the course of experiments it has been found, that in this way it is not only far easier to bring the ripping tab into the correct position, when wrapping on the wrapping paper, and to close the wrapping paper, but that this way of arranging the ripping tab can be effected entirely with the aid of 35 a machine.

In the accompanying drawing an example of 40 how the ripping tab may be formed according to the invention is shown:—

Figure 1 is a plan view of the carton *d* placed 45 on the wrapping paper which is laid out flat.

Figure 2 is a perspective view of the finished 50 package.

The fold *a* which is picked up out of the wrapping paper and in the figure lies below the plane of the drawing coincides, when the wrapping paper is being wrapped over the top edge of the carton, with the edge of the front wall of the 55 carton.

The middle part of the fold *a*, which lies at the upper edge of the front wall (Fig. 2) is the ripping tab. The lateral parts of the ripping tab lie at the upper edge of the side walls and 10 are covered and secured by the downwardly folded ends *b* of the wrapping paper as shown in the figure. The wrapping paper is secured in this position by the label *c*.

After the side edges of the ripping tab have 15 been torn in, which can easily be effected, the tab can be gripped between the thumb ball of the hand on one side and the other fingers of the hand on the other side and, by moving the gripping hand backwards can be used for tearing 20 open that part of the wrapping, which lies above the lid, and exposing the lid.

It is already known for opening newspapers, 25 wrappers and the like and for opening the paper wrappings of packages, to provide tearing strips 30 consisting of transverse pleats, and which extend transversely over the wrapper or over the wrapping of the package. In contradistinction thereto the present invention relates to an improvement of the known tearing devices, consisting of 35 a ripping tab arranged at the upper edge of the front wall of the box and open at the bottom, by means of which the part of the wrapping covering the top of the carton can be torn off.

What I claim is:

A device for ripping open the paper wrapping 40 of cartons in the form of prisms, for example, four-sided prisms, by means of a ripping tab, characterized by the feature that the ripping tab is formed by picking up the surface of the 45 wrapping paper and nipping it, and that the wrapping paper is wrapped around the carton in such a manner that the tab extends downwards from the top edge of the front of the carton, the ends of said tab being folded round the sides and covered by the parts of the wrapping paper which are folded downwardly from the top of the carton.
